CLAIM

The ornamental design for a garden bed corner post, as shown and described.

DESCRIPTION

FIG. 1 is a perspective view of a garden bed corner post showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the garden bed corner post.

The broken lines in the drawings depict portions of the garden bed corner post that form no part of the claimed design.

1 Claim, 9 Drawing Sheets
